UNITED STATES PATENT OFFICE.

DAVID S. JACOBUS, OF JERSEY CITY, NEW JERSEY, ASSIGNOR TO THE BABCOCK & WILCOX COMPANY, OF BAYONNE, NEW JERSEY, A CORPORATION OF NEW JERSEY.

REGULATING DEVICE.

Original application filed December 14, 1918, Serial No. 136,523. Divided and this application filed August 10, 1918. Serial No. 249,361.

To all whom it may concern:

Be it known that I, DAVID S. JACOBUS, a citizen of the United States, residing at Jersey City, in the county of Hudson and State 5 of New Jersey, have invented certain new and useful Improvements in Regulating Devices, of which the following is a specification.

My invention is disclosed in my prior 10 Patent No. 1,328,997, granted January 27, 1920, and of which the present application is a division.

My present invention relates to a regulating apparatus comprising a power cylinder 15 and its piston for operating a suitable controlling mechanism, the admission of fluid to the cylinder being controlled by a valve, the operation of the latter valve being responsive to variations in pressure in a closed receptacle. I have illustrated by invention in connection with a superheat limiting device, in which a closed receptacle containing a volatile liquid is placed in the path of the superheated steam, so that the pressure 20 within the closed receptacle varies in accordance with the temperature of the superheated steam. It is to be understood, however, that pressure variations could be brought about by means other than those 25 here specifically illustrated, and my present invention constitutes a means for regulating the admission of fluid to the power cylinder through a valve, the operation of which responds to variations in pressure.

My invention will best be understood by 35 reference to the accompanying drawings in which Figure 1 is a diagrammatic view illustrating my invention used in connection with a superheat limiting device; Fig. 2 is 40 a side view with certain parts in section of a modified form of apparatus embodying my invention; Figs. 3 and 4 are enlarged views, partly in section, of parts of the valve and stem of Fig. 2; Fig. 5 is a side 45 view, partly in section, of another modified form of apparatus embodying my invention; Fig. 6 is a top view of Fig. 5; Figs. 7, 8 and 9 are enlarged views of the operative mechanism and diaphragm of the 50 apparatus shown in Fig. 5; Fig. 10 is a side view, mainly in section, showing a balanced valve which may be used in connection with the apparatus in place of the valves illustrated in the forms of apparatus shown in

Figs. 1, 3 and 5, the valve being shown 55 closed; Fig. 11 is a view similar to Fig. 10 showing the valve open; Fig. 12 is a transverse section on the plane of the line 18—18 of Fig. 11; Fig. 13 is a transverse section on the plane of the line 19—19 of Fig. 11; Fig. 14 is a transverse section on the plane of the line 20—20 of Fig. 11; Fig. 15 is a side view, mainly in section, of another form of valve which may be employed for operating the power piston and which may be 60 used in place of the valves illustrated in the forms of apparatus shown in Figs. 1, 3 and 5; and Fig. 16 shows the same valve in open position.

In the adaptations, hereinafter described, 70 of my invention to superheater practice, I employ a thermostat placed in the path of the outgoing superheated steam. In the form shown this comprises a closed container for a volatile liquid, the temperature 75 of such liquid, and consequently the pressure of its vapor, varying as the temperature of the surrounding superheated steam varies. This vapor pressure generated in the container is utilized to set in operation 80 certain mechanisms to limit the temperature within the superheater setting and thus limit the degree of superheat. For the purpose of explaining the principle of operation of my invention, I have shown a diagrammatic arrangement in Fig. 1 in which the numeral 1 designates a portion of the superheated steam main. Within this main is a container in the form of a coiled pipe 2 closed to the steam and containing a volatile 90 liquid such as water, alcohol or mercury having a fixed boiling point for a given pressure. The container may have any appropriate form which will insure an effective impingement of the superheated steam 95 and a relatively large heating surface with the proper internal volume. The upper end of the coil 2 is secured in an opening in the cap 3 closing the end of the steam main, said cap having a chamber 4 from which a pipe 100 5 leads to a regulator. The coil 2 is only partially filled with liquid, the space above the liquid being filled with vapor, the pressure of which corresponds to the temperature to which the liquid is heated by the superheated steam. The latter regulator comprises a chamber 6 having a flexible dia- 105 phragm 7 upon which diaphragm rests a

disc 8. When water is used as the liquid in the coiled pipe 2 the chamber 6 is filled with water upon the surface of which oil is placed to prevent corrosion of the diaphragm 7, which is preferably of hardened steel. For a given steam temperature passing over the coil 2 there will be a given vapor pressure transmitted to the chamber 6, since the coil 2, chamber 4, pipe 5, cylinder 6 and diaphragm 7 constitute a closed evaporator, of which one part, the coil 2, is subjected to the heat of the steam in the main 1. This pressure acting upon the under side of the diaphragm 7 is transmitted 15 through the following mechanism:—

The post which bears on the disc 8 is pivoted to a lever 9 having its fulcrum at 10. To the free end of the lever 9 is attached the stem of a valve 11 which valve controls 20 the flow of a fluid under pressure, preferably water, entering through pipe 12 from a source of supply. From the valve chamber the fluid under pressure is delivered through a pipe 13 to a cylinder 14 having a piston 25 15, which latter is connected to a power lever 16 having its fulcrum at 16'. To the end of lever 16 is attached a rod 17, the movements of which rod are utilized to operate suitable doors to admit air to the 30 superheater and thus control the temperature thereof as more fully described in my prior application above referred to. When the valve 11 is closed, by a reduction of the vapor pressure on diaphragm 7, the power 35 lever 16 is restored to its normal position by a counterweight 16², the water in the cylinder being discharged through a valved pipe 18. The valve in the pipe 18 is partially open at all times, so that there is a 40 permanent outlet to the cylinder during its operation and the valve is not changed in position when the mechanism is in operation. The valve in the pipe 18 is so adjusted that during the time the water is 45 being admitted to the cylinder 14, through the pipe 13, the discharge through the pipe 18 is materially less than the rate at which the water is admitted through pipe 13. The upward movement of lever 9 is opposed by 50 a spring 9' and is limited by a stop 9².

The action of the regulator above described is to cause the vapor pressure generated in coil 2 to act through the regulator in such manner that when the temperature 55 of the superheated steam flowing through the main 1 exceeds that for which the apparatus is set, the lever 9 will be raised to thereby open valve 11 to admit water under pressure to the working side of piston 15.

60 When the piston 15 is moved, the power lever 16 will be moved and thereby the rod 17, to operate a mechanism which regulates the temperature of the superheated steam as more fully disclosed in my prior patent 65 above referred to. When the temperature

of the steam is reduced below that at which the apparatus is set, the valve 11 will be moved to its seat by the spring 9'.

On closing the valve 11 the water discharged through the valve in the pipe 18 will allow the power piston 15 to slowly regain its original position near the top of the power cylinder 14, the lever 16 having a counterweight 16² which moves the power piston 15 to its original position.

The advantage of allowing the water which operates the power piston 15 to escape at all times through a constricted opening is that it provides a simple means whereby the power piston 15 may return to its original position after the mechanism has been thrown into action, and further, there are special advantages in using this method as the apparatus may be operated through a very small movement of the valve 11. The method described is superior in these respects to one where the water is released from the power cylinder by means of a valve actuated by the same mechanism that actuates the valve 11, as the latter arrangement would require a much closer adjustment and would be much more liable to get out of order than the one described.

The pressure gauge 43, shown in Fig. 2, is acted on by the pressure transmitted from the coil 2 through the tube 5. This gauge has been found of great assistance in the operation of the superheater, as it is highly sensitive in indicating changes in temperature in the superheated steam, as changes in the pressure of the vapor in coil 2 depend upon changes in the temperature of the superheated steam.

The apparatus above described is set to operate at a temperature somewhat higher than the average amount of superheat given by the superheater and should the superheat, either accidentally or by design, attain the temperature to which the device is set, the latter will act to prevent a further increase of superheat. In the actual use of the device it has been found that by proper hand manipulation of the fires it is seldom called upon to act, but its use is, nevertheless, highly essential as it provides a safeguard against an excessive amount of superheat which might cause trouble in the power system.

In Figs. 2, 3 and 4, I have shown, more in detail than in Figure 1, the mechanism for operating the power lever 16, this mechanism embodying certain features of construction differing from that shown in the diagrammatic Fig. 1. Water has been used as the evaporating agent in coil 2, in the practical use of the device, herein described. After the apparatus has been installed, water is pumped into the coil 2 through a valved pipe 58 having a removable plug in its end, as shown. This filling takes place with

steam flowing through the main 1 and when the water has been heated, it is blown out through the open end of pipe 58 and the apparatus then refilled. By repeating this operation several times all the air is driven out of the apparatus and when it is finally filled, the surplus water is allowed to drip slowly from the pipe 58 until the pressure indicated by the gauge 43 corresponds to the temperature of the coil 2. This point can be readily determined as the pressure falls quickly on first allowing the water to drip from pipe 58, whereas the moment the pressure corresponding to the temperature of the coil 2 is reached, there is no further fall in pressure. When the apparatus is set up and in operation the discharge outlet of the valve at the end of the pipe 58 is closed by the plug. The diaphragm chamber 59 must be filled with oil, or with water and oil, before the coil 2 is filled.

The chamber 59, as shown, is formed with a projection 59' to limit the downward movement of the diaphragm 60. Resting upon the diaphragm is a strut or post 61 which bears against a knife edge 62 carried by lever 63. The tension of spring 9' may be adjusted by a nut 9" to hold the lever 63 firmly against the stop 9", and to provide the requisite resistance to the upward movement of the strut 61. To the end of the lever 63 is attached the spindle 64' of a valve 64 shown on an enlarged scale in Fig. 3. Said valve is formed so that it will take its position firmly on the seat 64". Both the seat 64" and the valve bonnet 64" may be readily taken out and replaced. When the valve is opened by the pressure generated in coil 2, acting through diaphragm 60, strut 61 and lever 63, water under pressure will be admitted through supply pipe 12 to cylinder 14, thereby moving piston 15, connected power lever 16 and rod 17 to effect the opening of doors as described in my prior application. As shown in Fig. 4, a spring 65 is interposed between the end of lever 63 and a supporting piece carried by the valve spindle 64'. When valve 64 is closed, the lever 63 and spring 65 are in the positions shown in Fig. 4, so that a certain amount of play will be allowed between the lever and a piece 65' carried by the spindle, and having an enlarged head above the end of the lever. The initial upward movement of lever 63 takes up the lost motion and the continued movement of the lever will bring it against the piece 65' to open the valve.

The valve casing is formed with a passage 66 leading from the upper end of cylinder 14 to the discharge pipe 18. A portion of the water entering through pipe 12 is permitted to escape through the passage 66, the amount being regulated by a valve at the end of the threaded piece 66'. The amount of water so escaping is much less

than that which flows inward through the valve 64 so that the piston 15 will be forced downward irrespective of the fact that some of the water escapes through the passage 66. The leakage water which passes upward around the lower part of the valve spindle 64' escapes through a passage 67 into the waste pipe 18. When the temperature of the steam flowing through the main 1 falls to a point which reduces the pressure in coil 2 sufficient to allow valve 64 to be closed by spring 9', the counterweight 16" attached to lever 16, will return the piston 15 to its normal position, the water in the cylinder escaping through passage 66 and pipe 18. Fig. 5 shows certain modifications of the apparatus of Fig. 2. This form employs a knife edge 68 and shackle 69 for transmitting the force from spring 9' to lever 63. The connection between the end of lever 63 and the valve spindle 64' has been modified by attaching a piece 70 to the end of the lever by a screw, as shown. Also in this form the threaded piece 66", for throttling the water flowing through passage 66, is carried by a sleeve 66".

The diaphragm and its casing have also been changed as indicated, that is, the member 71 in which the strut 61 is supported, is held by bolts 71', and in common with the first form described is of substantial construction in order to provide the rigidity and strength necessary for forming and maintaining a good joint at the edges of diaphragm 72. As shown, in the enlarged view Fig. 9, the member 71 is formed with a projection 71" and the diaphragm is firmly held between said projection and a corresponding depression in the base member 73. The lower end of strut 61 is seated in a cap 61' which fits into the central depression of diaphragm 72. The diaphragm has only a slight upward movement which is allowed for by providing a clearance as indicated at 72', the form of the diaphragm being of importance in the construction and operation of the apparatus. The amount that the cap 61' and strut 61 can rise is limited by allowing the proper clearance above the top of the cap and the face 71" of member 71. A certain amount of clearance is left between the top of the projecting stop 59' and the lower part of the diaphragm, this clearance being so regulated that should the strut 61 be forced downward to bring the diaphragm firmly against the stop, there will be no injury to the diaphragm. The form of diaphragm here shown is covered by my application, Serial No. 258,430 which is filed of even date.

Figs. 10 to 14 show a balanced valve for admitting water to the power piston, said valve comprising two members 74 and 75 screwed together as indicated and having, respectively, two faces 74' and 75' of the same form and dimensions. These valve

faces seat against corresponding stationary faces 76 and 77. The member 78, on which is formed the seat 76, is removably held by a pin 78' passed through its lower end. By 8 making the valve face 74' and its seat 76 of the same form and size as the face 75' and its seat 77, the valve will be balanced and will require but little force to open and close it as compared with an unbalanced 10 valve having the same capacity for the flow of water.

Figs. 15 and 16 illustrate a further modification in the valve for admitting water to the power cylinder and the means for operating it. In this form the valve 79 and its hollow stem 79' are preferably made in one piece. The body portion of the valve 79 is cylindrical and, when the valve is raised, moves as a piston in a cylinder formed in the 20 valve casing concentrically with and above the valve seat. The valve casing is formed with a passage 12' leading from the pipe 12 which is connected to a source of water under pressure, said passage opening into a space 25 in the casing below the valve so that an upward pressure will be exerted by the water on the valve. In the lower part of the valve body are two ducts 80 through which water is permitted to flow into the casing above the 30 valve. In the valve stem 79' are two sets of ducts 81 and 82, the latter being normally closed, as shown in Fig. 15, by a spindle 83 connected to the end of lever 63, said lever being actuated by pressure generated in the 35 coil 2 in the superheated steam main 1, as hereinbefore described. The spindle 83 passes through the valve stem 79' to near the lower end thereof, to provide a chamber 84. The ducts 81 afford communication between 40 the space above the valve 79 and the chamber 84, and the ducts 82 afford communication, when open as shown in Fig. 16, between said chamber and a chamber 85 opening into a passage 85' which latter dis- 45 charges into the waste pipe 18 through a nipple 85². When the spindle 83 is in its lower-most position so that it covers the ducts 82, the water pressure below and above the valve is equalized as the water is per- 50 mitted to enter the space above the valve through the ducts 80 and into the chamber 84 through the ducts 81, but cannot escape through the ducts 82. When the spindle 83 is raised by lever 63, the ducts 82 will be un- 55 covered, allowing the water above the valve to discharge to the waste pipe 18 and thus relieve the pressure above the valve. When this occurs, the water pressure below the valve will open it, allowing the water from 60 pipe 12 to enter the power cylinder 14, the valve in its opening movement causing its stem 79' to slide along the spindle 83. Surrounding the lower end of the valve stem is a spring 86 between the valve and a cap 65 87 screwed into the casing, said spring be-

ing compressed when the valve is raised. When the superheat is lowered to an extent which will cause the lever 63 to fall, spindle 83 will be moved downward thus closing the ducts 82 and allowing the water pressure to 70 build up in the space above the valve. When the pressure is equalized, the spring 86 will close the valve.

In Fig. 15 the power piston is shown as returning to its normal position after the valve 75 79 has been closed, the water above the piston during this time escaping through the passage 66 and thence to the waste pipe 18. A drain 14' near the bottom of the cylinder 80 14 conducts any water which may leak by the piston to the waste pipe 18. Any water which leaks from the chamber above the valve 79 around the hollow stem 79', or through the ducts 82, when closed up spindle 83, will flow into the chamber 85 and passage 85' and finally into the waste pipe.

The spindle 83, valve 79 and valve seat 79² are made of metal which will resist corrosion. The valve seat is formed with indentations 79³ to permit engagement of a 90 special tool for the insertion and removal of the seat. The inlet pipe 12 is provided with a strainer 12² to prevent any solid matter being carried in with the water which operates the power piston.

What I claim and desire to secure by Letters Patent of the United States is:—

1. In a regulating device, a movable member, a cylinder and its piston for moving said member, a valve for controlling the admission of a fluid under constant pressure to said cylinder, a controlling mechanism connected to said valve and actuated by a fluid under variable pressure and means to return said member to normal position, said cylinder having a permanently open outlet for the discharge of the fluid therefrom.

2. In a temperature regulating device, a movable member, a cylinder and its piston for moving said member, a valve for controlling the admission of a fluid under constant pressure to said cylinder, a closed evaporator having a portion thereof located in the medium whose temperature is to be 110 regulated, a controlling mechanism connected to said valve and operated by the variable pressure in said evaporator and means to return said member to normal position, said cylinder having a permanently open outlet for the discharge of the fluid therefrom.

3. In a regulating device, a movable member, a cylinder and its piston for moving said member, a balanced valve for controlling the admission of a fluid under constant pressure to said cylinder, a controlling mechanism for said valve and actuated by a fluid under variable pressure and means to return said member to normal 125 130

position, said cylinder having a permanently open outlet for the discharge of the fluid therefrom.

4. In a regulating device, a movable member, a cylinder and its piston for moving said member, a valve for controlling the admission of a fluid under constant pressure to said cylinder, a diaphragm connected to a source of variable pressure fluid, a lever 10 connected to said valve and to said diaphragm, and constructed and arranged to open said valve when the pressure against said diaphragm reaches a predetermined amount, means to return said member to normal position, said cylinder having a permanently open outlet for the discharge of the fluid therefrom.

5. In a regulating device, a movable member, a cylinder and its piston for moving said member, a controlling mechanism operated by fluid under variable pressure, a valve to control the admission of a fluid under constant pressure to said cylinder, said valve having a body member formed 20 as a piston, means normally to apply fluid pressure equally on each side of said valve piston, mechanical means normally to hold said valve on its seat and means, operated by said controlling means, to relieve the fluid pressure on one side of said piston, whereby the fluid pressure on the other side of the piston will raise said valve from its seat.

6. In a regulating device, a movable member, a cylinder and its piston for moving said member, a controlling mechanism operated by fluid under variable pressure, a valve to control the admission of a fluid under constant pressure to said cylinder, 30 said valve having a body member formed as

a piston having a chamber therein, ducts in said body member to connect said chamber with the source of fluid pressure surrounding said valve, relief ducts adapted to be connected to said chamber, whereby the 45 pressure therein may be relieved, mechanical means to hold said valve on its seat, and a pilot valve, connected to said controlling means, to open said relief ducts, whereby the fluid pressure surrounding said valve 50 may open said valve against the pressure of said mechanical means.

7. In a regulating device, a movable member, a cylinder and its piston for moving said member, a controlling mechanism 55 operated by fluid under variable pressure, a valve to control the admission of a fluid under constant pressure to said cylinder, said valve having a body member formed as a piston, means normally to apply fluid 60 pressure equally on each side of said valve piston, mechanical means normally to hold said valve on its seat and means, operated by said controlling means, to relieve the fluid pressure on one side of said piston, 65 whereby the fluid pressure on the other side of the piston will raise said valve from its seat, and means to return said power actuated member to normal position, said cylinder for actuating said member having a 70 permanently open outlet for the discharge of the fluid therefrom.

In testimony whereof I have hereunto signed my name in the presence of two subscribing witnesses.

DAVID S. JACOBUS.
